UNITED STATES PATENT OFFICE.

ALBERT L. HARVEY, OF WILKINSBURG, AND DAVID H. HUNTER, OF PITTSBURGH, PENNSYLVANIA, ASSIGNORS TO WESTINGHOUSE ELECTRIC AND MANUFACTURING COMPANY, A CORPORATION OF PENNSYLVANIA.

MOTOR-CONTROL SYSTEM.

Application filed October 9, 1920, Serial No. 415,816. Renewed May 14, 1924.

To all whom it may concern:

Be it known that we, ALBERT L. HARVEY, a citizen of the United States, and a resident of Wilkinsburg, in the county of Allegheny and State of Pennsylvania, and DAVID H. HUNTER, a citizen of the United States, and a resident of Pittsburgh, in the county of Allegheny and State of Pennsylvania, have invented a new and useful Improvement in Motor-Control Systems, of which the following is a specification.

Our invention relates to motor-control systems and it has particular relation to such systems as are employed for starting induction and synchronous motors.

The object of our invention is to provide means for protecting induction or synchronous motors from improper starting, especially where the starting operation is performed by manual operation of circuit breakers.

Heretofore, an induction motor has been started by closing a starting circuit breaker, which established a circuit between the low-voltage terminals of an auto-transformer and the motor and afterwards opened the starting circuit breaker, and then closing a running circuit breaker which connected the motor directly to a supply source of energy.

If the running circuit breaker was not closed within a relatively short interval of time after the starting circuit breaker had been opened, the speed of the induction motor would so decrease that, when the motor was connected directly to the source of energy, it would cause a dangerous electrical overload upon the motor.

For a better understanding of our invention, reference may be made to the accompanying drawing—

Figure 1 of which is a diagrammatic view of a motor-control system embodying our invention.

Fig. 2 is a diagrammatic view of a slightly modified motor-control system embodying our invention.

Referring particularly to Fig. 1, an induction or synchronous motor 1, having a primary winding 2 and a secondary member 3, is electrically connected, by a circuit comprising a knife-blade switch 4, to supply conductors 5. An auto-transformer or other voltage-reducing device 6 and a starting circuit

breaker 7 are employed to start the motor 1. A running circuit breaker 8, having a locking device 9, is employed for connecting the primary winding 2 of the motor 1 directly to the source of energy. A time-element relay 10 and an auxiliary relay 11 control the operation of the locking device 9 of the running circuit breaker 8.

The starting circuit breaker 7 is actuated by an arm 12 which is pivotally mounted upon a pin 13. The running circuit breaker 8 is actuated by an arm 14 which is pivotally mounted upon a pin 15. The arm 14 is provided with a handle 16.

The locking device 9 of the circuit breaker 8 comprises a rod or bar 17 which is slidably mounted in a guiding member 18. A projection 19 of L-shape extending from the arm 14 may be brought into engagement with the rod 17. The rod 17 may be actuated by a lever 21 which comprises a member 22 of L-shape pivotally mounted upon a pin 23 mechanically connected to the bar 17 by a pin 24.

A resilient member or spring 25a is secured to a stationary member or pin 26 and to the free end of the member 22 in such way that it tends to force the bar 17 toward the handle 16 of the circuit breaker 8. The respective ends of the bar 17 and the projection 19 on the arm 14 of the circuit breaker 8 are so designed that the circuit breaker 8 may be actuated to its open position, regardless of the condition of the remainder of the control system. The circuit breaker 8 may not be closed until the bar 17 has been withdrawn sufficiently to permit the projection 19 of the arm 14 to clear the end of the bar 17.

The member 22 of the lever 21 may be operated by energizing a coil 25, which actuates an armature member 26a. The armature member 26a is pivotally connected to the member 22.

The motor 1 is started by first closing the knife-blade switch 4 and then closing the starting circuit breaker 7. The primary winding 2 of the motor 1 is then energized by a circuit established from the supply conductors 5, through the knife switch 4, a set of conductors 28, auto-transformer 6, a set of conductors 29, which are connected to the low-voltage terminals of the auto-trans-

former 6, contact members 30 of the starting circuit breaker 7, and conductors 31, to primary winding 2 of induction motor 1.

The secondary member 3 of induction motor 1 may be energized by induction from the member 2 thereof or it may be energized from an independent source of direct current, if it is a synchronous motor. After the motor 1 begins to rotate and it has been brought to a desirable speed, the starting circuit breaker 7 is opened and the running circuit breaker 8 is closed.

The starting circuit breaker 7 and the running circuit breaker 8 are mechanically interlocked by a rod or bar 32, which is pivotally mounted upon a pin 33, and so engages the arms 12 and 14 of the circuit breakers 7 and 8, respectively, that it is impossible for them to occupy their closed positions at the same time. Therefore, when the starting circuit breaker 7 has been closed, the running circuit breaker 8 can not be closed until the starting circuit breaker has first been opened.

The starting circuit breaker 7 is provided with an auxiliary contact member 34 which establishes a circuit for energizing the actuating coil 35 of the relay 11, when the starting circuit breaker 7 is closed. The circuit, comprising the actuating coil 35 of the relay 11 and the auxiliary contact member 34 of the starting circuit breaker 7, extends from one of the supply conductors 28 through conductor 36, contact member 34 of starting circuit breaker 7, conductor 37, actuating coil 35 of relay 11, conductor 38, auxiliary contact member 39 of running circuit breaker 8, and conductor 40 to a second conductor 28.

The actuating coil 35 of the relay 11 being energized, the relay 11 will close, thereby establishing a holding circuit from one of the supply conductors 28 through conductors 36 and 42, contact member 43 of the relay 11, conductors 44 and 37, actuating coil 35 of the relay 11, conductor 38, contact member 39 of running circuit member 8, and conductor 40 to a second conductor 28.

A second circuit is also established, by closing the relay 11, from one of the supply conductors 28 through conductors 36 and 42, contact member 43 of relay 11, conductors 44 and 45, contact member 46 of time-element relay 10, actuating coil 25 of locking device 9 of circuit breaker 8 and conductors 47 and 40 to a second conductor 28.

The actuating coil 25 of locking device 9, being energized, causes the armature member 26a to actuate the member 22 which, in turn, will draw the bar 17 in a direction away from the projection 19 of the arm 14 of the circuit breaker 8.

After the operator of the control system has decided that the induction motor 1 has obtained sufficient operating speed, he opens

the starting circuit breaker 7 by manually actuating the arm 12 thereof.

When the starting circuit breaker 7 has assumed its lower or open position, a circuit is established from the conductors 28 through conductor 36, contact member 34 of circuit breaker 7, conductor 49, actuating coil 50 of time-element relay 10, conductor 38, contact member 39 of running circuit breaker 8, and conductor 40, to conductors 28.

The actuating coil 50 of the time-element relay 10 being energized, contact member 46 will slowly rise until it breaks the circuit comprising the actuating coil 25 of the relay device 9 of the circuit breaker 8. The time consumed by the relay 10 before breaking this circuit is controlled by the dash pot 51 and the shape of the contact member 46.

It is apparent that, once the starting circuit breaker 7 has opened, the running circuit breaker 8 must be closed before the time-element relay 10 occupies its open position. If the running circuit breaker 8 is not closed within this interval of time, the actuating coil 25 will be de-energized by the relay 10 occupying its open position and the arm 17 will then prevent the downward movement of the handle 16 of the circuit breaker 8. It will then be necessary to repeat the operations in the required order before the motor can be brought to full speed.

When the circuit breaker 8 is closed, a circuit is established from supply conductors 5 through knife-blade switch 4, set of conductors 52, contact members 53 of circuit breaker 8, and conductors 31, to primary winding 2 of induction motor 1.

When the running circuit breaker 8 is brought to its closed position, the auxiliary contact member 39 thereof assumes its open position, thereby breaking the circuit comprising the actuating coil 35 of the relay 11, thereby causing the relay 11 to open. When the relay 11 is opened, the actuating coil 25 of the locking device 9 of the circuit breaker 8 is de-energized.

Referring to Fig. 2, corresponding apparatus and circuits are designated by the same numerals as in Fig. 1.

Time element relay 10 is provided with a contact member 46, similar to one shown in Fig. 1 with the exception that it is slidably mounted on an armature member 54 and is positioned thereon by means of a resilient member 55 and a nut 56. The dash pot 51 is so arranged as to prevent quick downward movement of the armature member 54. The slow downward movement of the armature member 54 is at first compensated for by the spring 55 which maintains the contact member 46 in its closed position.

The operation of this system is begun, in the usual manner, by closing the knife-blade

switch 4 and the starting circuit breaker 7, thereby energizing the primary winding 2 of the induction motor 1. The auxiliary contact member 34 is so mechanically connected to the starting circuit breaker 7, that, when the starting circuit breaker 7 is closed, the contact member 34 completes a circuit from one of the conductors 28 through conductor 60, contact member 34 of the starting circuit breaker 7, conductor 61, actuating coil 50 of time-element relay 10, conductor 62 to a second conductor 28.

When this circuit is established, the actuating coil 50 is energized, thereby causing the time-element relay 10 to close. This operation may be arranged to consume a predetermined interval of time by adjusting the relay 10 in order that the armature member 54 shall have a slow upward movement. By having the time-element relay 10 slowly assume its closed position, too rapid opening of the starting circuit breaker 7 and closing of the running circuit breaker 8 is prevented.

As soon as the contact member 46 of the time-element relay 10 has assumed its closed position, the actuating coil 25 of locking device 9 of circuit breaker 8 is energized by a circuit which is established from one of the conductors 28 through conductors 60 and 64, contact member 46, actuating coil 25 and conductor 65 to a second conductor 28. The actuating coil 25, being energized, causes the armature member 26 to disengage the bar 17 from the projection 19 of the arm 14 of the circuit breaker 8, and thus permits the circuit breaker 8 to be closed after the starting circuit breaker 7 has been opened.

As soon as the starting circuit breaker 7 has been opened, the actuating coil 50 of the time-element relay 10 is de-energized and the contact member 46 would quickly fall to its open position were it not for the compensating action of the resilient member 55. After a certain time has elapsed the resilient member 55 will no longer be able to maintain contact member 46 in its closed position because of the descent of the armature member 54.

Unless the circuit breaker 8 is closed before the time-element relay 10 is opened, the actuating coil 25 will be de-energized, and the locking device 9 will prevent the circuit breaker 8 from being opened. The motor 1 can then be brought to full speed only by repeating the operations that have been described.

It is apparent that, by constructing a motor-control system for induction or synchronous motors in accordance with our invention, it will be impossible to start the motor improperly and that such a system gives full protection against closing a running circuit breaker, when an induction motor is idle, or when the motor is operat-

ing at such a low speed that it would be dangerous to connect it directly to the line.

While we have shown our invention in a preferred form, it is apparent that minor modifications may be made in the apparatus employed and in the arrangement of circuits without departing from the spirit thereof. We desire, therefore, to be limited only by the scope of the appended claims.

We claim as our invention:

1. The combination with a dynamo-electric machine and a plurality of manually actuated switches, of means for preventing said switches from being closed simultaneously, and means for limiting the time for closing one switch after opening another switch.

2. In a motor-control system, the combination with a motor and a source of electrical energy, of a transformer, a manually actuated starting switch for connecting said motor to said transformer, a manually actuated running switch for connecting said motor to said source, and means for limiting the time for closing said running switch after opening said starting switch.

3. In a motor-control system, the combination with a motor and a source of electrical energy, of a voltage-reducing device, a switch for connecting said motor to said voltage-reducing device, a second switch for connecting said motor to said supply source, means for preventing said switches from being closed simultaneously and means for locking said second switch in its open position to limit the time for closing said second switch after opening said first switch.

4. In a motor-control system, the combination with a motor and a source of electrical energy, of an auto-transformer, a starting switch for connecting said motor to said transformer, a running switch for connecting said motor to said supply source, means for preventing said running switch from closing until after the opening of said starting switch, and means, comprising a locking device and a time-element relay, for limiting the time for closing said running switch after said starting switch has been opened.

5. In a motor-control system, the combination with a motor and a source of electrical energy, of a transformer, a starting switch for connecting said motor to said transformer, a running switch provided with a locking device for preventing the closure thereof and a magnetic release therefor, means for preventing said switches occupying their closed positions at the same time, a time-element relay for limiting the time between opening the starting switch and closing the running switch and means coacting with said starting switch for operating said relay.

6. In a motor-control system, the combination with a motor and source of electrical

- energy, of a transformer, a starting circuit breaker for connecting said motor to said transformer, a running circuit breaker for connecting said motor to said supply source, means for preventing said circuit breakers from occupying their closed positions simultaneously, a locking device for preventing the closing of said running circuit breaker, a magnetic release for said locking device, a time-element relay for controlling said magnetic release, a contactor controlled by said starting circuit breaker for starting said relay to operate upon the closure of said starting circuit breaker.
7. The combination with a motor, of a manually actuated starting switch for energizing said motor, a manually actuated running switch for increasing the energization of said motor, and means for preventing the closure of said running switch to limit the period of time between the opening of said starting switch and the closing of said running switch.
8. The combination with a motor, and a source of energy, of an auto-transformer, a starting circuit breaker for connecting said motor to said auto-transformer, a running circuit breaker for connecting said motor to said source, a locking device for said
- running circuit breaker, a releasing coil for said device, a time-element relay having an actuating coil for controlling the energization of said releasing coil, and a contactor mechanically connected to said starting circuit breaker for controlling the energization of said actuating coil.
9. In a motor-control system, the combination with a motor, a source of energy, and a voltage-reducing device, of a starting circuit breaker for connecting said motor to said device, a running circuit breaker for connecting said motor to said source of energy, means for preventing said running circuit breaker from closing until after first closing said starting circuit breaker for a predetermined minimum interval of time and then opening said starting breaker, said means preventing said running circuit breaker from closing if said running circuit breaker is not closed within a predetermined period after opening said starting circuit breaker.

In testimony whereof, we have hereunto subscribed our names this first day of October, 1920.

ALBERT L. HARVEY.
DAVID H. HUNTER.
